UNITED STATES PATENT OFFICE.

WALTER A. WILLIAMS, OF LEXINGTON, OKLAHOMA.

DOUBLETREE AND LINE-HOLDER.

No. 895,927.

Specification of Letters Patent.

Patented Aug. 11, 1908.

Application filed December 16, 1907. Serial No. 406,676.

To all whom it may concern:

Be it known that I, WALTER A. WILLIAMS, a citizen of the United States, and a resident of Lexington, in the county of Cleveland and State of Oklahoma, have invented certain new and useful Improvements in Double-trees and Line-Holders, of which the following is a specification.

This invention is an improvement in double-trees and line holders for use thereon; and the invention consists in certain novel constructions and combinations of parts, as will be hereinafter described and claimed.

In the drawing Figure 1 is a perspective view of the apparatus ready for use, the tongue being broken away in section. Fig. 2 is a cross-section on about line 2—2 of Fig. 1. Fig. 3 is a cross-section on about line 3—3 of Fig. 1. Fig. 4 is a detail view of the tongue plate, and Fig. 5 is a detail view of the double-tree plate.

The tongue A, double-tree B, and swingletrees C may in general respects be of ordinary construction. The double-tree B is pivoted by the king bolt D to the pole or tongue A, and the swingletrees C are pivoted by the bolts C' to the ends of the double-tree and are braced by the loops C², as best shown in Fig. 3 of the drawing.

The tongue plate A' shown in detail in Fig. 4, is formed with a broad head-like portion A² at its rear end perforated for the bolt D and upon which the double-tree rocks in the use of the invention. This head A² is bolted securely to the tongue and the plate A' extends forwardly to a point in advance of the arch rod of the double-tree plate and forms a bearing therefor.

The double-tree plate E has a back plate E' secured to the under side of the double-tree, and the forwardly extending arch rod E² which slides at its middle portion upon the plate A' is preferably shouldered at E³ on opposite sides of said central portion E⁴ to limit the rocking movement of the double-tree, and a cover plate F is secured at its rear end by a bolt D above the double-tree and extends thence forwardly and is bent down to overlie the front end of the tongue plate A', and is bent to form an upwardly curved keeper F' in which the central portion E⁴ of the arch rod E² slides as the double-tree rocks in the use of the invention.

A strap G is secured at its rear end to the rear end of the tongue or pole, and bends up-

wardly and lies at its front end G' upon the double-tree, and receives the king bolt D.

The line holder is in the form of a bar H, extending longitudinally above the double-tree and having at its ends the downwardly projecting portions H' having at their lower ends feet H² held by the bolts C' of the swingletrees, the said rod H being supported midway between its ends by the upright H³ having its rearwardly deflected foot H⁴ secured by the double-tree. This line holder having the intermediate and the end supports, and extending over the top of the double-tree and to the central pivot of the swingletrees, operates to prevent the lines from getting under the inner ends of the swingletrees.

The double-tree plate forms a brace for said double-tree and also by its arch rod E² a stay, which is especially constructed at its middle portion to coöperate with the tongue plate and the cover plate F in limiting the rocking movement of the double-tree in the use of the invention, while the tongue plate A' forms at its rear end a wear plate for the double-tree, as will be understood from the drawing.

I claim—

1. The improvement herein described comprising the tongue, the plate thereon, the double-tree, the double-tree plate having a stay plate secured to the under side of the double-tree and a forwardly extending arch rod provided at its middle with the reduced portion sliding upon the tongue plate, a cover plate secured upon the tongue and having a bearing portion overlying the central reduced portion of the arch rod and forming a keeper therefor and provided at its rear end with the upwardly projecting portion overlying the double-tree, the king bolt pivoting the double-tree in connection with the tongue, the swingletrees, the bolts pivoting said swingletrees to the double-tree, and the line rod having the intermediate and end depending portions secured by the king bolt and the pivot bolts of the swingletrees, all substantially as and for the purpose set forth.

2. The improvement in whiffle trees herein described consisting in combination with the tongue and a double tree pivoted thereto, of swingletrees pivoted to the double tree, a cover plate overlying at its rear end the double tree and extending thence forward over the tongue, a tongue plate underlying at its rear end the double tree and extending

thence forward over the tongue and underlying at its front end the front end of the cover plate, the latter being deflected to form a guide for an arch rod, the said double tree, 5 cover plate, and tongue plates having alined openings for the king bolt, a king bolt passing through said openings, an arch rod secured at its ends to the double tree and extending thence forwardly over the tongue 10 and operating midway between its ends between the cover plate, and tongue plate, a

line rod extending over the double tree, and an upright rod connected with the line rod midway between its ends and extending thence downwardly and secured by the king 15 bolt, all substantially as and for the purposes set forth.

WALTER A. WILLIAMS.
